UNITED STATES PATENT OFFICE.

HENRY H. LUEDECKE, OF AUSTIN, TEXAS.

SANITARY BED-SPRING COVER.

1,383,734.

Specification of Letters Patent. Patented July 5, 1921.

Application filed November 30, 1920. Serial No. 427,306.

To all whom it may concern:

Be it known that I, HENRY H. LUEDECKE, a citizen of the United States, residing at Austin, in the county of Travis and State 5 of Texas, have invented certain new and useful Improvements in Sanitary Bed-Spring Covers, of which the following is a specification.

This invention relates to improvements 10 in sanitary covers for attachment to the spring of a bed intermediate the spring and mattress.

An important object of the invention is the provision of a sanitary covering for use 15 upon beds, which is saturated in a germicidal solution to repel vermin and especially noxious insects.

A further object of the invention is the provision of a sanitary cover of the above 20 described character which is so constructed as to maintain the bedding and especially the mattress placed thereupon, impervious to moisture, and drafts of air, and protecting the mattress from dust, dirt and rust 25 from the bed spring.

Other objects and advantages will be apparent during the course of the following detailed description.

In the accompanying drawings, forming 30 a part of this specification, and in which like reference characters designate like parts throughout the same,

Figure 1 is a perspective view of a bed having the sanitary spring covering attached 35 to the spring.

Fig. 2 is a plan view partly in section showing the sanitary bed spring cover, and the construction thereof.

Fig. 3 is a fragmentary view showing several 40 elements of construction of the device prior to the complete assemblage thereof.

Fig. 4 is a fragmentary cross sectional view showing an end construction of the cover.

In the drawings, wherein for the purpose 45 of illustration is shown a preferred embodiment of my invention, the letter A designates a bed, couch or similar apparatus; having the spring B thereon; upon the upper 50 surface of which is attached the sanitary bed spring cover C. The sanitary bed spring cover C comprises the container D, and the insert E.

The container D preferably comprises the 55 top cover 10 formed of a double thickness of

material, which may be paper, or some substantially impervious textile. The bottom cover 11 is preferably the same material as the top cover 10, and likewise may comprise a double thickness of material. The top and 60 bottom covers 10 and 11 respectively, are assembled with the insert E intermediate, and the abutting surfaces of the covers and insert are glued together to form a substantially unitary structure. In order that the 65 insert E may be securely and entirely sealed within the container D, the lateral edges of the bottom cover are first turned as at 12, upon the bottom surface 13 of the cover 11, entirely around and about all edges of the 70 cover. The edges 15 of the top cover 10 are then bent downwardly and turned to overlie the turned edges 12 of the bottom cover, entirely around all sides of the cover, thus providing a sealed container D for the 75 insert E. Stitching 16 is then provided about the cover C and engaging the turned edges 13 and 15 of the bottom and top covers respectively, as well as engaging the insert E and the abutting portions of the top and 80 bottom covers 10 and 11. By reason of the stitching 16 a sealed structure is thus provided for holding the insert E.

The insert E is preferably of some absorbent material such as heavy sanitary gauze 85 or some textile material. It is treated prior to its insertion into the container D with some germicidal solution, preferably odorless, and one which is not of sufficient strength to cause deterioration of the cover 90 itself.

In order to provide suitable means for securing the sanitary cover to the spring B, eyelets 20 are inserted through the cover structure C and preferably to engage the 95 inturned surfaces 12 and 15. It is preferred that three eyelets 20 be disposed upon the end surfaces of the cover D which are situated adjacent the head and foot of the bed, and that one eyelet 20 be situated upon 100 each side of the cover C, and intermediate the ends having the three eyelets. Strands of rope 21 of size sufficient to engage the spring B are loosely disposed within the aperture 22 of the eyelets 20, being provided for the purpose of securely fastening the sanitary cover C to the bed spring B. 105

In assembling a bed spring cover, the absorbent cover is first glued to the inside structures of the covers 10 and 11; the end 110

and side edges 12 of the bottom cover 11 are then inturned upon the surface 13 of the bottom cover; the inturned portions 15 next being inturned to overlie the inturned 5 edges 12, and the structure stitched together as at 16. The eyelets 20 are next inserted and the strands of rope attached therein. The paper or other material forming the covers 10 and 11 is preferably treated with 10 same insecticidal solution and is substantially impervious to moisture by reason of its composition.

It is to be understood that the form of 15 my invention herewith shown and described is to be taken as a preferred example of the same, and that various changes in the shape, size and arrangement of parts may be resorted to, without departing from the spirit of the invention or the scope of the 20 subjoined claims.

I claim:

1. In a sanitary spring cover, comprising in combination, a top cover, a bottom cover, an absorbent germicidally treated insert between 25 said covers, said bottom cover inturned upon itself about its lateral edges, and having the lateral edges of the top cover inturned and disposed over the inturned lateral edges of the bottom cover,

and means for fastening said covers and 30 insert together to form an impervious structure.

2. In a sanitary bed spring cover, the combination, of a top cover of a double thickness of insecticidally treated material, 35 a bottom cover of a double thickness of insecticidally treated material, a germicidally treated insert of absorbent material, disposed intermediate said top and bottom covers and glued thereto, said bottom cover 40 inturned around its edges upon itself, said top cover inturned upon its edges to overlie the inturned edges of the bottom cover, stitching through said inturned edges of the top and bottom covers, eyelets through 45 said top and bottom covers, and fastening strands disposed in said eyelets.

3. A spring cover comprising in combination a top cover, a bottom cover, an insert between said covers, said bottom cover in-turned upon itself about its lateral edges and having the lateral edges of the top cover inturned and disposed over the in-turned lateral edges of the bottom cover, and means for fastening said covers and insert together to form a spring cover.

HENRY H. LUEDECKE.
